[57] **CLAIM**

The ornamental design for an above-ground swimming pool, as shown and described.

DESCRIPTION

FIG. 1 is a top plan view of the above-ground swimming pool showing my new design;

FIG. 2 is an elevation view of the above-ground swimming pool of FIG. 1 as it appears when looking toward the swimming pool from the outside thereof from any location around the pool; and

FIG. 3 is a fragmentary transverse section taken along line 3—3 of FIG. 1 in the direction of the arrows and showing the details of the circular coping which extends without interruption all around the upper part of the pool.

FIG. 1

FIG. 3

FIG. 2
